UNITED STATES PATENT OFFICE.

CHARLES GAMER, OF FORT WORTH, TEXAS.

GAS-PRODUCER.

No. 873,037.

Specification of Letters Patent.

Patented Dec. 10, 1907.

Application filed May 24, 1907. Serial No. 375,393.

To all whom it may concern:

Be it known that I, CHARLES GAMER, a citizen of the United States, residing at Fort Worth, in the county of Tarrant and State of Texas; have invented certain new and useful Improvements in Gas-Producers, of which the following is a specification.

This invention relates to an apparatus for producing gas and particularly to apparatus for producing gas from lignite or other gas producing material, and the object is to provide inexpensive apparatus which is simple in construction and operation and to provide apparatus of the kind for the use of individual enterprises whether large or small. Apparatus may be prepared for furnishing gas to be used for driving small motors, thus making it practical for a small factory to manufacture its own gas. Apparatus may also be made for producing gas for a city or several manufacturing establishments or machine shops.

Other objects and advantages will be fully explained in the following description and the invention will be more particularly pointed out in the claims.

Reference is had to the accompanying drawings which form a part of this application and specification.

Figure 1 is a side elevation of the apparatus. Fig. 2 is an elevation of the apparatus, looking at the left side of Fig. 1. Fig. 3 is a vertical section of the furnace and the gas cleaners. Fig. 4 is a plan view of the lower shifting grate. Fig. 5 is a plan view of the casing for the grate shifting racks.

Similar characters of reference are used to indicate corresponding parts throughout the several views.

This apparatus is provided with a furnace 1 which is lined with fire brick 2. The furnace is provided with a chute 3 and a hopper 4 for feeding lignite to the furnace. When lignite is not being fed to the furnace, the chute 3 is closed by a rotary valve 5 which may be operated by a crank or handle 6. For the purpose of clearing the clinkers which form near the bottom or lower part of the combustion chamber, shifting grates 7 and 8 are provided. The upper grate 7 has a cutting edge 9. The lower grate 8 stands normally within the furnace to support the material during combustion, but may be withdrawn to let the ashes fall to the ash box 11. For the purpose of shifting the grates 7

and 8 the grates are provided with racks 10 and 12 which may be formed integral with the grates 7 and 8 respectively. A casing 13 is attached to the side of the furnace and communicates or opens into the furnace. The grates 7 and 8 can be withdrawn from the furnace within the casing 13. The racks 10 and 12 are moved by pinions 14 and 15 which are provided with shafts 16 and 17. A casing 18 for the pinions 14 and 15 and racks 10 and 12 is attached to the casing 13. The shafts 16 and 17 are journaled in the sides of the casing 18. Any suitable handle or crank may be used to turn the shafts 16 and 17. For the purpose of breaking clinkers from the side or from the brick lining 2, a scraper 19 is provided. The scraper has a number of blades or arms which are or may be formed integral with the body 19 thereof. The two blades 20 which are on the side of the furnace adjacent to the casing 13 are far enough apart to receive the racks 10 and 12 and the blades all operate on the outside of the grates, that is, between the grates and the lining 2. The scraper is elevated and lowered by racks 21 which may be formed integral with the body portion 19. The racks 21 are driven by pinions 22 and the pinions 22 are driven by the shaft 23. The blades of the scraper may be run up whenever it is necessary to clear the lining 2 of clinkers.

The gas escapes from the furnace 1 through a box 24 which is attached to and communicates with the furnace. The gas passes from the box 24 by a circuitous course through a series of cylinders 25, 26, 27, 28, 29, 30, and 31. Cylinders 25 and 26 communicate through a box 32. Cylinders 26 and 27 communicate through a box 33. Cylinders 27 and 28 communicate through a box 34. Cylinders 28 and 29 communicate through a box 35. Cylinders 29 and 30 communicate through a box 36. Cylinders 30 and 31 communicate through a box 37. The boxes 33, 35, and 37 have openings 38 which are closed by covers 39. The covers 39 are held on by yokes 40 which engage lugs formed on the sides of the boxes and by hand bolts 42 which screw through the yokes 40 and press on the covers 39. The upper boxes and the lower boxes and the cylinders are held in operative relation by rods 43 which engage lugs 44 formed on the boxes. As the products of combustion pass from the furnace, they are made to go through a circuitous

course in the cylinders and each cylinder is provided with a series of separators in order to separate the gas from the tar and other products. In cylinders 25 to 30 inclusive the separators 45 are horizontally disposed and each separator is somewhat more than a half disk. The separators cause a change of direction of the course of the gas at each separator. This action will cause the tar to be deposited or arrested on the separators and the gas will pass on through the cylinders. The tar, when separated from the gas, will drip down from the separators and escape from the cylinders into the lower boxes and then through the pipes 46 and under the surface of water in the box 47. A variation in the form of the separators is shown in Fig. 3, cylinder 31. A spiral conveyer 47 serves to separate what tar is left in the gas. The tar from the cylinder 31 passes through the pipes 48 and 49 to the trough or box 47. The gas is collected in the storage cylinder 50 to be distributed to the motor to be used. A vent pipe is connected with the cylinder 25. The spiral conveyer 47 in cylinder 31 will permit the gas to escape in larger volumes or particles than would escape from cylinders having the separators 45. The separators 45 are on a rod and can be removed.

The operation has already been described. The vertically arranged cylinders receive the products of the combustion and separate the gas from the tar and other matter and the tar is collected in a trough or box. The lower grate stands normally in the furnace. The upper grate may be run in as often as necessary to break off the clinkers that form near the bottom of the furnace. When the clinkers form on the side of the brick lining, the scraper may be run by the racks and pinions to scrape the clinkers from the brick. The blades of the scraper run in the notches in the periphery of the grate. The grate reaches beyond the blades and rests on the support 52 formed on the furnace. Guides 53 are provided for the scraper and attached to the furnace wall.

Provision is made for supplying water to the cylinders through which the products of combustion are passing. A pipe 54 is connected to the box 33. Water may be introduced with the pipe 54 into box 33. As the water runs or drops down through the cylinders 26 and 27, the gas will become charged with moisture to some extent and the moisture will have a beneficial effect on the gas. The water will also aid in causing a flow of the tar to the receptacle 47.

Coke, lignite, or other gas producing material may be burned in the furnace.

Sufficient draft is created in the furnace to furnish air for combustion purposes by the engine which takes the gas from the tank 50. The removal of the gas from the tank 50 tends to create a vacuum in the chambers 25 to 31 inclusive and also in the furnace. The air will be taken through the furnace doors and the furnace needs no other means for providing air for combustion purposes. The actual use of the gas producer herein shown demonstrates that the air supply is amply sufficient.

Having fully described my invention, what I claim as new and desire to secure by Letters Patent, is,—

1. A gas producer comprising a furnace for the combustion of lignite, a series of vertically arranged cylinders having communication with said furnace, removable separators horizontally disposed in said cylinders, boxes, each box forming a connection of one cylinder with the next cylinder in succession, drain pipes connected to the boxes at the lower ends of said cylinders, and means for collecting the gas for distribution.

2. A gas producer comprising a furnace for the combustion of lignite, a series of vertically arranged cylinders having communication with said furnace, removable separators mounted in said cylinders, connecting boxes, each box connecting one cylinder with the next cylinder in succession, rods engaging lugs on said boxes and holding said boxes and cylinders in operative relation, drain pipes connected to the boxes at the bottom of said cylinders, a box containing water for immersing the ends of said drain pipes, and means for collecting the gas.

3. A gas producer comprising a receptacle for the combustion of gas producing material, a series of vertically arranged cylinders, a series of boxes at the upper and lower ends of said cylinders, each box connecting a cylinder with the next cylinder in succession, a rod running through each cylinder, separators mounted on said rods and forming a circuitous passage through said cylinders, drain pipes connected to boxes at the lower ends of said cylinders, and means for collecting the gas.

In testimony whereof, I set my hand in the presence of two witnesses, this 17th day of May, 1907.

CHAS. GAMER.
